BALANCE WHEEL ROLLER REMOVER

Edward George Schmelzer, Oberlin, Kans.

Application November 5, 1951, Serial No. 254,838

3 Claims. (Cl. 81—6)

1

This invention is a balance wheel roller remover for use in connection with the removal of the roller from the balance staff of watches of various sizes, clocks and the like.

As is well known, in watch and clock structure the balance wheel is provided with a balance staff having a disk or roller mounted thereon and it frequently becomes necessary to remove the roller from the balance staff. The primary object of the present invention is to provide a device wherein operations of this character may be easily, quickly and effectively carried out with the minimum of opportunity for damage to the balance staff or the balance wheel in removing the roller.

A further object of the invention is to provide a remover of the character stated which automatically adjusts itself to balance wheels of different sizes.

A further object of the invention is to provide a roller abstractor of the character stated wherein the balance wheel is so supported as to permit of the roller removing operations by simplified means, and wherein the balance wheel may be easily and quickly applied to the support and with equal facility may be removed therefrom.

With the foregoing objects in view, together with others which will appear as the description proceeds, the invention consists in the novel construction, combination and arrangement of parts, all as will be more fully described hereinafter, illustrated in the drawings, and particularly pointed out in the claims.

In the drawings:

Fig. 1 is a top plan view of a balance wheel 35 roller removing device embodying the invention.

Fig. 2 is a side elevation of the structure shown in Fig. 1.

Fig. 3 is a vertical longitudinal sectional view taken substantially upon line 3—3 of Fig. 1, and 40

Fig. 4 is a bottom plan view of the device as shown in Fig. 2.

The balance wheel remover of my invention includes means whereby the holder is supported in place for convenient operation of a punch and in a manner well known to those having knowledge of the art. To this end, the support for the balance wheel remover includes a base 5, from the lower end of which and centrally with respect thereto is a hollow post 6 to be seated in the support. The base 5 has a flat elongated upper surface or platform as shown, upon which are slidably arranged balance wheel supporting jaws indicated at 7. These jaws rise from heads 8 which slidably rest upon the upper surface of

10

the platform 5 and are confined in this sliding movement between spaced parallel guide arms 9 formed integral with the platform or base 5. The upper extremities of the jaws 7 are notched or recessed as at 10 in order to firmly engage with the balance staff of a balance wheel resting upon the upper ends of the jaws. The notches 10, when the jaws are in clamping position, will vertically align with the central opening 11 in the post 6.

Each of the heads 8 is provided with a longitudinally disposed bore or recess 12, the said recesses opening into the heads from the adjacent faces thereof, and an expansion spring 15 13 has its ends seated in each of the bores or recesses. A guide pin 14 is disposed within the coiled expansion spring 13 to prevent the latter from snarling. It is thus seen that the expansion spring 13 tends normally to force the heads 8 and the jaws 7 thereof apart or in separated relationship.

Projecting from one side of the platform or base 5 is a support 15, constituting a flat platform as shown. Swingly mounted for movement in a horizontal plane upon the support or platform are clamp arms 16. Each of the said arms has a loop 17 at one end for pivotal engagement upon their respective supporting posts 18 rising from the supporting or platform 15 near the opposite ends thereof. These clamp arms are so shaped as to extend around the heads 8 and in engaging position therewith and are inwardly bent at their ends, as shown particularly in Figs. 1 and 3 so as to be in overlapping relationship beyond one side of the support. The extreme inner ends of the clamp arms are upwardly bent as shown particularly in Figs. 1 and 2 to provide posts 19, to which are connected the ends of a compression spring 20. It will be observed, particularly with reference to Fig. 1 of the drawings, that the posts 19 are disposed between the pivot posts 18 and the sliding jaws so that normally the compression spring 20 exerts pressure upon the clamp arm 16 inwardly of the support so that the said clamp arms will engage the sliding heads 18 and force the same together in clamping relationship. To this end, it is obvious that the compression spring will possess sufficient strength to overcome the tension of the expansion spring 13 which normally tends to separate the clamp arms.

When it is desired to apply a balance wheel to the roller remover, the post 6 is firmly seated in a proper support, whereupon the clamping arms 16 are moved to head disengaging position, or in

50

55

the position indicated by dot and dash lines in Fig. 1. When moved to this position, it will be seen that the posts 19 will have passed dead center with the supporting pivot posts 18, whereupon the compression spring 20 will maintain the arms in disengaged position as shown by dash and dot lines in Fig. 1. The jaws of the holder being thus free, the expansion spring 13 will force the heads 8 to the limit of their outward movement, with the jaws 7 in separated or spaced relationship. The balance wheel to be repaired is then placed upon the upper ends of the jaws with the balance staff disposed downwardly between the said jaws. The clamp arms 16 are then moved to operative position as shown in Fig. 1, forcing the heads 8 together against tension of expansion spring 13 and with the upper ends of the jaws 7 firmly engaged upon opposite sides of the balance wheel staff. It will be understood that the compression spring 20 will be sufficiently strong to maintain the heads 8 and their attached jaws 7 in tight engagement with the work, through the instrumentality of the clamp arms 16.

From the foregoing it is obvious that I have provided means of extremely simple nature for properly supporting the balance wheels in proper position to be operated upon in the removal of the roller from the balance staff, the construction and arrangement being such that rollers or balance wheels of various sizes may be automatically accommodated and properly supported for the removal operation.

I claim:

1. In a balance wheel remover, a supporting post, a platform carried by said post, a pair of jaw heads slideable upon said platform toward or away from one another, an expansion spring interposed between said heads to normally hold the latter in separated position, a pair of pivots rising from said platform to one side of said heads and in spaced relationship, a clamp arm pivoted at one end to each of said posts and ex-

tending forwardly into engagement with their adjacent heads, and a contractile spring connecting said arms and normally forcing the same toward one another into engagement with said heads, said contractile spring possessing tensile strength in excess of the strength of said expansion spring.

2. In a balance wheel remover, a platform, a pair of jaws mounted on said platform for sliding movement with respect to one another, spring means tending normally to maintain said jaws in spaced apart position, a pair of arms pivoted at one end in spaced relationship to one another on said platform and having portions engaged respectively with the outer ends of said jaws, upstanding posts at the inner ends of said arms and offset from the pivots thereof, a contractile spring connecting said posts, and said contractile spring possessing tensile strength exceeding the tensile strength of said spring means.

3. In a balance wheel remover, a platform, a pair of balance wheel supporting jaws mounted on said platform for sliding movement toward and away from each other, an expansion spring tending normally to force said jaws apart, an arm pivoted at one end near each end of said platform, said arms having portions engaged with the outer ends of their adjacent jaws, a contractile spring connecting said arms for forcing the same against said jaws to move the latter toward one another, and said contractile spring possessing tensile strength in excess of the strength of the said expansion spring.
